UNITED STATES PATENT OFFICE.

JAMES QUIGLEY, OF PHILADELPHIA, PENNSYLVANIA.

TOOL-HOLDER FOR METAL-WORKING MACHINES.

SPECIFICATION forming part of Letters Patent No. 681,139, dated August 20, 1901.

Application filed April 13, 1901. Serial No. 55,765. (No model.)

To all whom it may concern:

Be it known that I, JAMES QUIGLEY, a citizen of the United States, residing in Philadelphia, Pennsylvania, have invented certain 5 Improvements in Tool - Holders for Metal-Working Machines, of which the following is a specification.

My invention relates to certain improvements in means for holding tools to the heads 10 of metal-working machines, such as planers.

The object of my invention is to provide 15 means whereby the tool can be used considerably longer than heretofore, and yet will be held rigidly to the head of the machine. This object I attain in the following manner, reference being had to the accompanying drawings, in which—

Figure 1 is a perspective view of my improved tool-holder. Fig. 2 is a sectional view 20 showing a long tool and my improved holder secured to the head of the planing-machine. Fig. 3 is a similar view showing a short tool clamped in position; and Fig. 4 is a sectional view on the line 4 4, Fig. 2.

25 The ordinary metal-planing tool, for instance, should be clamped by two clamp-plates, so as to hold it rigidly in position, and when the tool is so short that only one clamp-plate can be used then it has to be discarded.

30 Consequently there is considerable loss, as tool-steel is expensive. By my invention I am enabled to use a tool until there is very little left of the body of the tool to clamp to the head.

35 A is the head of a planing-machine in the present instance.

B B are the clamp-plates, secured to the head by studs C C, having nuts c c in the present instance.

40 E is the tool having a cutting portion e of any suitable shape, depending upon the work to be planed.

D is my improved tool-holder. This holder has side flanges d' d', which form a cavity in 45 which the tool E snugly fits. The flanges d' d' are preferably slightly tapered at the rear, so that the upper portion i of the tool-holder will rest against the head A, while the lower portion, as shown by dotted lines in 50 Fig. 3, will be clear of the head. This allows

the tool E to be rigidly clamped between the face d of the tool-holder and the surface a of the head when the nuts c are turned to cause the clamp-plates B to press tightly against the holder. The sides d' of the holder are of 55 such a width as to confine the tool E laterally, and the holder is also of sufficient width to fit snugly between the studs C, so that there will be no lateral movement of the holder on the head or the tool within the 60 holder. Thus by my invention I am enabled to hold either a long tool, as illustrated in Fig. 2, or hold a tool as short as that shown in Fig. 3 rigidly to the head, and I have by practical experiments made very heavy cuts 65 with a tool using my improved holder without dislodging the tool, and these cuts could not be made heretofore with the tool, say, of such length as to be held by both clamp-plates. 70

In order to hold my improved tool-holder in position when the nuts c c are backed off to adjust the tool, a lip d² is formed upon the face d of the holder, which is arranged to extend over one of the clamp-plates B. I preferably form this lip by cutting the upper end of the holder and forcing out the lip, as shown in Fig. 1, and this lip will rest upon the upper cross-bar, as shown in Figs. 2 and 3. 75

I claim as my invention—

1. As a new article of manufacture, a tool-holder for securing tools to the heads of metal-working machines, said tool-holder having a front plate and side flanges forming a cavity for the reception of a tool and so shaped that 85 it can be clamped to the head of a metal-working machine, one end of each side flange being deeper than the other end, substantially as and for the purpose described.

2. The combination in means for securing 90 a short tool to the head of a metal-working machine, of a head, two clamp-plates, one mounted above the other, a tool-holder of a length to be clamped by the two plates, said holder having side flanges for the reception 95 of a tool, and means for securing the clamp-plates, tool-holder and tool to the head, substantially as described.

3. The combination of a head, clamp-plates, means for securing the clamp-plates to the 100

head, a tool, a tool-holder fitting over the tool, the said tool-holder being shaped to bear only against the tool at its lower end, and against the head at its upper end, substantially as described.

4. As a new article of manufacture, a tool-holder for securing short tools to the head of a metal-working machine, said holder consisting of a face-plate and two flanges forming a cavity for the tool, and a projection on the holder arranged to engage one of the

clamp-plates by which the holder is secured to the head, substantially as described.

In testimony whereof I have signed my name to this specification in the presence of 15 two subscribing witnesses.

JAMES X QUIGLEY.
